(57) **CLAIM**

The ornamental design for a suitcase, as shown and described.

DESCRIPTION

FIG. 1 is a front left perspective view of a suitcase, showing my design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The dash-dash broken lines illustrate portions of the suitcase that form no part of the claimed design. The dash-dot-dash broken lines represent the boundaries of the claim that form no part of the claimed design.

1 Claim, 6 Drawing Sheets(56)
